ABSTRACT: This disclosure relates to a finger splint of the kind known as a "lively" splint for assisting digital action of a person suffering from partial paralysis, muscle spasm, dystrophy or other conditions affecting normal movements of the digits of the hand. The splint comprises at least two digit-engaging members spaced apart and connected by spring means so that when one member is engaged with the thumb and the other with a finger, the spring means tends to move the members apart in such a manner as to move the fingers in a hand-opening direction.

FINGER SPLINT

This invention relates to a finger splint of the kind known in the art as a "lively" splint, that is, a device for assisting digital action of a person suffering from partial paralysis, muscle spasm, dystrophy or other conditions affecting normal movement of the digits of the hand.

An object of the invention is to provide a simple yet effective lively splint for supplementing the extensor muscles of the phalangeal joints, that is for assisting opening movements of one or more fingers and/or the thumb.

According to this invention a finger splint of the kind known as a "lively" splint comprises at least two digit-engaging members spaced apart and connected by spring means in such a manner that when one of said members is engaged with the thumb and the other of said members is engaged with a finger, the spring means tends to move the members apart in such a manner as to move the finger in a hand-opening direction. Preferably the spring means is a curved length of spring steel wire, to each end of which is attached one of the digit-engaging members. A thumb-engaging member is preferably of U-shape and a finger-engaging member is either a ring or U-shape trough which is fitted over the relevant finger. If desired the splint could include more than one member for engaging each digit, or it could include more than one member for engaging several digits; for example; a splint in accordance with the invention could have two aligned U-shaped thumb-engaging trough-like members and two spaced rings or troughs for engaging two fingers. The spring steel wire is preferably sleeved, for example with rubber or a plastics material.

The length and gauge of wire will be chosen to suit the patient, so as to give sufficient power to open the digits after flexing. The wire may be preformed to a shape suitable for the patient's hand, for instance so that it may be disposed at the palm side, or around the back of the hand.

If desired, a retaining strap may be fitted for encircling the wrist to ensure that the wire is kept close to the hand.

An example of the invention will now be described with reference to the accompanying drawing, the single figure of 5 which is a perspective view of a splint in accordance with the invention, with a hand shown in dotted lines.

Referring to the drawing, the back of a hand 6 is shown, with thumb 7 and index finger 8. The finger splint has a U-shaped thumb-engaging trough-like member 4 having spaced 10 apart ends 5. This member 4 fits over the lower part of the thumb with the ends 5 directed outwardly. The splint also has a ring (or trough) 3 which fits over the lower part of the index finger 8 although the ring (or trough) could instead fit over the middle part of the finger, as indicated by 3A. Welded at 15 4A and 3B respectively to the member 4 and the ring 3 is a bent length 1 of spring steel wire with a sleeve 2 of plastics material. This length of wire is so connected to the member 4 and ring 3, and is of such length, that it lies conveniently against the palm side of the hand.

20 The length of wire tends to move the member 4 and ring (or trough) 3 apart, thus assisting movement apart of the thumb and index finger.

I claim:

1. A finger splint comprising a curved length of spring steel 25 wire having a sleeve of pliable material and adapted to lie against the palm of the hand of a patient, a U-shaped thumb-engaging trough-like member attached to one end of the said wire, and ring means at the other end of said wire for engaging the index finger of the hand, the said length of wire tending to 30 move the thumb and said finger apart in such a manner as to aid in moving the said thumb and finger in a hand-opening direction, said length of wire being axially joined to said trough-like member at one leg thereof and axially joined to said ring means at one side thereof.

UNITED STATES PATENT OFFICE
CERTIFICATE OF CORRECTION

Patent No. 3,533,405 Dated October 13, 1970

Inventor(s) Dennis William Collins

It is certified that error appears in the above-identified patent and that said Letters Patent are hereby corrected as shown below:

In the heading, "Priority June 10, 1967, Great Britain, 25,953/66" should read -- Priority June 10, 1966, Great Britain, 25,953/66 --. In the heading, after "Inventor Dennis William Collins, Cambridge, England" insert -- assignor to Hugh Steeper Limited, a British Company. --.

Signed and sealed this 17th day of August 1971.
